UNITED STATES PATENT OFFICE

JOHN M. KRAUSE, OF LOS ANGELES, CALIFORNIA, ASSIGNOR OF ONE-HALF TO NORMAN E. HALL, OF LOS ANGELES, CALIFORNIA

DESIGN FOR A TOY TOP

Application filed May 9, 1930. Serial No. 35,556. Term of patent 3½ years

To all whom it may concern:

Be it known that I, JOHN M. KRAUSE, citizen of the United States, residing at Los Angeles, in the county of Los Angeles and State of California, have invented a certain new, original, and ornamental Design for a Toy Top, of which the following is a specification, reference being had to the accompanying drawing, which forms a part thereof.

I claim:

The ornamental design for a toy top as shown.

In testimony whereof I hereunto affix my signature.

JOHN M. KRAUSE.
